UNITED STATES PATENT OFFICE.

CHARLES HENRY PARKER, OF CODSALL, ENGLAND.

RETORT FOR THE DISTILLATION OF COAL AND SIMILAR CARBONACEOUS SUBSTANCES.

Application filed January 27, 1928, Serial No. 249,963, and in Great Britain September 25, 1926.

This invention relates to apparatus for the distillation of coal and similar carbonaceous substances.

The invention relates to that type of vertical retort in which a number of retort cavities or chambers are formed in a single casting, and the invention has among its objects to provide a retort of such form in which the area of the external walls to which heat is applied is extensive, and so that while the retort cavities or chambers are formed in one casting, heat is applied to the charges from each side of the retort cavities or chambers formed therein, so that by such means the transmission of heat is rapidly effected from the opposite sides and ends to the centre part of the charge.

The invention is especially applicable in the distillation of coal at low and medium temperatures and for the production of a smokeless fuel having a high or moderately high volatile content.

According to the invention the transverse section of the retort cavities or chambers is substantially rectangular or oblong and the retort cavities or chambers are of identical size and form and are slightly enlarged in dimensions towards their lower ends. The respective retort cavities or chambers are disposed in line and in parallel relation, but their vertical end or side walls are not in alignment. Each individual retort is connected to its neighbour by a part of one of its lateral walls. Thus a part of each lateral wall is common to adjacent retorts, that is to say each of the individual retorts has one of its end walls in advance of the end wall of the retort to the rear of it, so that by such means angular vertical cavities are formed by the external faces of the adjacent ends and part of the side walls of the retorts. It will thus be understood that the right hand side wall of one retort protrudes forward so that this extension may complete the left hand side wall of the next retort, the right hand side wall of which is similarly extended to form the left hand wall of the next retort on the other side. Thus on the opposite sides of the casting a series of vertically disposed angular recesses are formed by the respective end walls of each of the retorts and by part of the adjacent side walls thereof and thus the respective retorts are connected together in opposite positions merely by a part of the side wall which is common to adjacent retorts. By such means it will be understood

that heat may be directly applied to each of the retort cavities or chambers from four sides and that the only part of the retort cavities or chambers at which the heat is not directly applied is the portion of side wall common to and connecting adjacent retorts.

It will be understood that the upper and lower extremities of the metal casting are formed with integral flanges horizontally disposed, upon the uppermost of which a hood fitting may be applied common to all the retorts or retort cavities within the casting and this hood may serve to form an upper chamber above the retorts or retort cavities into which the gases and vapours produced in the distillation may pass and issue through an outlet in the upper part of the hood fitting, and the hood fitting may be provided with a cover plate or closure which may be removed to permit of the funnel of the charging hopper passing into the mouth of the hood so as to permit of the coal or other carbonaceous substances falling into the respective retorts or retort cavities. At the lower end of the metal casting a common cover or bottom plate may be applied or any other means provided to close the lower ends of the retorts or retort cavities. Where such a cover plate is provided this may conveniently be hinged so that on being released at one side it may fall down to permit of the charge being released from the retorts.

As a practical example the retorts or retort cavities in cross-section may be provided of the dimensions $4\frac{1}{2}$ by 11 inches at the top and $5\frac{1}{2}$ by 12 inches at the bottom, the retort cavities being of a length of nine feet. It is preferred to provide the width of that part of the said wall which is common to adjacent retorts about one half the total width of the side wall.

It will be understood that the invention is not limited to the manner in which such a metal casting may be used and mounted within a setting, nor yet to the manner in which the heat may be applied to the retort, nor yet is it limited to the dimensions above indicated. It is preferred that the cross-section of the retorts may be substantially rectangular or oblong, but here again no limitation is involved to such a cross-section.

The accompanying drawings illustrate a construction of retort casting in accordance with the invention, by way of example.

Figure 1 is a side elevation of the casting.
Figure 2 is a plan view of the upper end.

Figure 3 is a sectional plan view taken on the line AA of Figure 1.

Referring to the drawings, the retort casting illustrated comprises a block of four retorts, each retort cavity *a* being of oblong transverse section, the ends of the section being of semi-circular form. The retort cavities are so disposed in the casting that the major axes of their respective transverse sections are disposed at an angle of 45° to the major axis of the transverse section of the casting, and thus, while they are disposed in parallel relation, the adjacent retorts have their adjacent lateral walls common only to the extent of half the width, as at *a*¹, and external angular cavities *a*² are formed by the external faces of the adjacent ends and part of the side walls of adjacent retorts. By such a disposition of the retort cavities the respective retorts are provided with ample heating surfaces for their effective operation.

The retort cavities *a* increase in dimensions towards the lower ends and thus the cross-section of the casing is also increased in area so that the lower flange plate *c* is of correspondingly larger dimensions than the up-

per flange plate *b*. Strengthening webs *b*¹, *c*¹ are provided between the respective flange plates *b*, *c* and the exterior lateral walls of the outer retorts. The upper flange plate *b* is advantageously slotted, as at *b*², for the reception of bolts by which a suitable hood fitting may be secured in position thereon. The lower flange plate *c* may be similarly provided for the reception of the mounting for the bottom cover plate.

I claim:

A battery of vertical retorts for the distillation of coal and similar carbonaceous material, comprising a unitary casting having a single row of retort chambers therein, each of said chambers being of oblong cross section and increasing in dimension from the upper end to the lower end thereof, the major axis of each chamber being disposed at an angle of substantially 45 degrees to the center line of the battery casting as a whole, whereby substantially one-half of the wall of each intermediate chamber is an outer wall of the casting, said casting having reinforcing means integral with the flat portion of the outer walls of the end chambers.

CHARLES HENRY PARKER.
